METHOD OF AND APPARATUS FOR
FRACTIONATING

Merrell Robert Fenske, State College, Pa., assignor to The Pennsylvania State College, State College, Pa., a corporation of Pennsylvania

Application June 26, 1933, Serial No. 677,754

14 Claims. (Cl. 196—139)

This invention relates to a method of and apparatus for fractionating, and with regard to certain more specific features, to fractionating towers for separating mixed vapors into their components.

Among the several objects of the invention may be noted the provision of a fractionating tower of the class described which has a greatly improved fractionating efficiency for its height, a fractionating tower providing improved means for contacting, within a short space, a maximum of ascending vapors with a maximum of descending scrubbing liquid, such contact being accomplished in a manner leading to optimum intimacy of contact; a fractionating tower of the "packed" type wherein such difficulties as channelling of the reflux liquid stream are obviated; a fractionating method wherein a plurality of evenly constituted, relatively small streams of reflux liquid are maintained separately against the vapors being scrubbed, and including means for forming said small streams of reflux liquid in such manner that all streams will contain substantially identical quantities of liquid; a fractionating tower having a greatly reduced pressure drop between its ends, as compared with prior types of fractionating towers; and the provision of fractionating towers of the class described which are relatively simple in construction and operation. Other objects will be in part obvious and in part pointed out hereinafter.

The invention accordingly comprises the elements and combinations of elements, features of construction, and arrangements of parts, and steps and sequence of steps, which will be exemplified in the structures hereinafter described, and the scope of the application of which will be indicated in the following claims.

In the accompanying drawings, in which are illustrated several of various possible embodiments of the invention,

Figures 1A and 1B together constitute a longitudinal section of a fractionating tower embodying the present invention, Fig. 1A being the bottom section, and Fig. 1B the top section, of the tower;

Figures 2A and 2B together constitute a longitudinal section of a tube or column comprising part of the tower of Figs. 1A—1B;

Fig. 3 is a horizontal cross-section of the tower of Fig. 1B, taken substantially along line 3—3 of Fig. 1B;

Fig. 4 is a side elevation of a fractionating tower similar to that of Figs. 1A—1B, but of relatively greater length;

Fig. 5 is a horizontal cross-section of the tower of Fig. 4, taken substantially along line 5—5 of Figures 4 and 6;

Fig. 6 is a vertical section of a distributor section comprising part of the tower of Fig. 5, taken substantially along line 6—6 of Fig. 5;

Fig. 7 shows a number of types of packing elements suitable for use in the towers of Figures 1 through 6;

Figures 8A and 8B together constitute a longitudinal section of an alternative embodiment of the invention, suitable particularly for vacuum distillations; Fig. 8A being the bottom section, and Fig. 8B the top section, of the tower;

Fig. 9 is a longitudinal enlarged section of a single tube and rod comprising part of the tower of Figs. 8A—8B;

Fig. 10 is a horizontal cross-section of the tower of Fig. 8A, taken substantially along line 10—10 of Fig. 8A;

Fig. 11 is a horizontal cross-section of the tower of Fig. 8A, taken substantially along line 11—11 of Fig. 8A;

Fig. 12 is a horizontal cross-section of the tower of Fig. 8B, taken substantially along line 12—12 of Fig. 8B; and,

Fig. 13 is an enlarged, somewhat distorted view of the packing elements of the tower of Figs. 8A—8B.

Similar reference characters indicate corresponding parts throughout the several views of the drawings.

The process of fractionating mixed vapors, such as those which come off a petroleum still or the like, consists essentially in scrubbing an ascending current of the mixed vapors with a descending liquid, commonly called the "reflux" liquid. As the vapors come into contact with the liquid, the heavier of the higher boiling components of the vapor are condensed in the liquid and so washed on down the tower. If the tower is thermally insulated, so that there is no considerable heat loss (i. e., the process is adiabatic), then the condensation of the vapor to a liquid gives off heat, which is in turn utilized to vaporize the lighter components of the reflux liquid, the vapors thus formed joining the primary vapors and proceeding upwardly in the tower. Thus, as the fractionating continues, the vapors, as they rise in the tower, become progressively richer in low boiling components, while the liquid reflux, as it descends in the tower, becomes progressively richer in high boiling components. The ultimate result is that the low boiling components all accumulate at the top of the tower, while the high

boiling components accumulate at the bottom, and thus fractionation is achieved.

Two factors contribute to the effectiveness of the separation. First, the larger the ratio of descending reflux to ascending vapors, the more probable it is that the vapors will be effectively scrubbed of their higher boiling fractions. Second, the effectiveness depends upon the degree of intimacy of contact between the reflux and the vapors, for without thorough contact no separation whatever is possible.

The customary, and most widely-used type of fractionating tower heretofore, was the bubble plate tower which comprised a series of plates arranged in vertical order, each plate carrying a liquid level of reflux thereon, and each plate being provided with means for bubbling the ascending vapors through the reflux liquid thereon. Provision was also made for draining the reflux liquid progressively downwardly. Fractionating towers of this type, which will not be described in great detail, usually consist of from ten to sixty plates. If the vapor-liquid contact on each plate were perfect, that is, if equilibrium were actually established during the time that the bubble of vapor was in contact with the reflux liquid, there would be accomplished one perfect distillation, and the tower would be said to have a "perfect" or "theoretical" plate. However, in actual use, equilibrium conditions are by no means reached, and an efficiency factor is adopted to express the ratio of actual to theoretical enrichment. In ordinary towers of this type, the efficiency is from 50 to 80 per cent., averaging about 60 per cent. This means (say, when the efficiency is but 50%), that two plates are actually needed to do the work that one could theoretically do.

Coupled with this factor requiring an excessive number of plates is the fact that comparatively wide spacing between the plates is necessary. This is because of liquid entrainment incident to the turbulence created as the vapors bubble through a plate, and the entrained liquid must be given sufficient space to settle out before the vapors are bubbled through another plate. Another reason for wide spacing is found in the back-pressure on individual plates occasioned by an increased rate of throughput, which back-pressure might, if the plates were too close together, cause the reflux liquid to back up through the overflow pipe to the plate above, and thus spoil the fractionating conditions.

For these reasons, plates are, on the average, spaced apart from 1 to 2 feet. So with an average plate efficiency of 60%, a vertical height of 20 to 40 inches is required to achieve a fractionation equivalent to one theoretically perfect plate. This height, 20 to 40 inches, represents the "height equivalent to a theoretical plate" factor, hereinafter referred to as the "H. E. T. P.". For a bubble plate type fractionating tower, therefore, the H. E. T. P. is large, and a very high tower is required for any degree of perfect separation. The present invention is concerned primarily with reducing the H. E. T. P. factor, so that a tower of high fractionating ability can be made in a relatively short length.

Another type of fractionating tower comprises a column of the "packed" type, in which a tube is filled with packing material and the reflux liquid allowed to trickle slowly downwardly over this material against the upward flow of the vapors. The packing material, which is of many different shapes and types, causes a high degree

of intimacy of contact between the reflux liquid and the vapors, and the efficiency of such materials as fractionating means is considerably more nearly perfect than that of the bubble plate. Further, no liquid entrainment or back-pressure difficulties are found in this type of tower, as there is no turbulence of contact as in the bubble plates and no liquid levels to set up back-pressures. In small-scale operations, such as laboratory-scale fractionations, therefore, the efficiency of a packed column tower is immensely greater than that of a bubble plate tower. For instance, with the separation of benzene and carbon tetrachloride in a packed column about 28 inches long and $\frac{3}{4}$ inch in diameter, an H. E. T. P. factor of $1\frac{1}{2}$ inches was obtained.

It is when the simple type of packed column tower is enlarged in diameter to a commercial size (to accommodate a large throughput) that the difficulties commence, and the fractionation efficiency drops off rapidly. This is due to the channeling of the reflux liquid streams as they progress downwardly through the packing. It will be apparent that for a packed column to operate with maximum efficiency, the liquid stream must be broken up into as large an area as possible for greater contact with the vapors. But the normal tendency is for a liquid to reduce its surface area for a given mass, and not to increase its area as desired. So the distributed liquid streams in a large-diameter column naturally come together, exposing the vapors to less and less area per unit mass of liquid. This coalescing of the liquid streams is called "channeling", and the greater the diameter and height of the column, the more pronounced is such channeling.

To reduce the channeling effect in packed columns it has heretofore been proposed to redistribute the liquid stream periodically at certain levels in the tower. That is, the channeling is conceded, but the stream is freshly subdivided at frequent intervals by means of distributors, as they are called. A system of distributors considerably increases the efficiency of the packed type of tower for commercial sizes, but as larger diameter towers are needed the redistribution problem becomes increasingly complicated, so that it becomes apparent that redistribution is not the ideal solution to the problem of making a large diameter packed tower as efficient as a small diameter packed column.

The present invention departs from previous developments along the line of redistribution in packed towers and proceeds upon a new line. Instead of attempting redistribution with its attendant difficulties, the present invention provides a large-diameter tower that is made up of individual units comprising the highly efficient small diameter columns. Large throughput is thus accomplished by multiplying the number of small capacity, small-diameter columns, rather than by increasing the diameter of a single column, in this way preserving the high efficiency of the small-diameter column and obviating the difficulties of channeling. Proceeding in this manner, there is practically no end to the capacity which may be achieved, for to increase the capacity, all that is necessary is to increase the number of unit columns.

The design of such a tower made up of a large number of unit columns is not, however, without its difficulty. To achieve a uniform fractionation in each of a large number of small columns (which is necessary in order to obtain uniform quality products from all of the columns),

provision must be made for equal distribution of the vapors to the columns, equal packing material (for equal surface contact area) in the individual columns, and equal reflux ratios in each 5 of the columns. This latter in turn requires an equal amount of reflux liquid in each column. The accompanying drawings illustrate towers which conform to these conditions.

Referring now more particularly to Figures 1A and 1B, it will be seen that the fractionating tower of the present invention comprises cylindrical outer jacket sections 1, 3, and 5, which are each provided with suitable flanges and bolts whereby they may be assembled as a single tower. Below 10 the lower section 1 is a bottom section 7, which is in the form of an inverted dome and terminates in a relatively large-diameter vapor entrance conduit 9. Above the upper section 5 is a similar dome-shaped top 11. The bottom and top sections 15 7 and 11 are provided with flanges to match the flanges of the sections 1 and 5, respectively.

The bottom flange 13, and top flange 15 of the section 1 continue as plates across each end of the section 1, which plates are drilled to accommodate a large number of parallel unit column tubes 17 (see also Fig. 3). The tubes 17 are secured firmly in place in the plates 13 and 15 by expanding their ends, in the same manner as heat exchangers have heretofore been constructed. A spacer plate 19 (see Fig. 1A) may also be provided, if the tubes 17 are unusually long and require additional support, but in general the tubes 17 are sufficiently rigid to maintain themselves in the desired spaced relation and no spacer plate 19 is required. The space exterior to the tubes 17 is dead air space, and serves excellently as heat insulating means to give the tower as a whole its adiabatic characteristics.

The tubes 17 are open at each end. They are 40 each filled to within a few inches of the top (see Figures 2A and 2B) with packing material 21, which may comprise any suitable material having a high ratio of surface area to free space (the surface area determining the area of liquid surface) for the liquid-vapor contact, while the free space permits the flow of the vapors without too great obstruction and without too great pressure drop in the tube. Various types of packing material, as shown in Fig. 7, are suitable. Referring 45 to Fig. 7, A indicates a chain packing, B a simple wire carding tooth, C a bent wire carding tooth, D a crimped wire, E a single turn, open wire helix, F a crossed-wire unit, G a multi-turn wire helix, and H an ordinary copper rivet, all 50 of which are more or less suitable for present purposes. The problems of the choice of a suitable packing material are treated with more detail in my copending application for Letters Patent Ser. No. 677,755 filed June 26, 1933 to which reference is hereby directed. At the lower end 55 of each tube 17 a grating 22 (Fig. 2B) may be provided, if necessary, to hold the packing material in place.

Between the top flange 15 of the lower section 60 1 and the bottom flange 23 of the intermediate section 3 (Fig. 1B) is clamped a ring 25, which includes four outlet pipes 27 arranged ninety degrees apart (see also Fig. 3). The ninety degree spacing permits even withdrawal of the vapors, 65 as will be indicated hereinafter, and the take-off system in this respect resembles a piezometer arrangement for gas pressure measurement.

The intermediate section 3 has the aforementioned bottom flange 23 and a top flange 29 as

well. The flanges 23 and 29 extend across the ends of the section 3 in the same manner as the flanges of section 1, to form supporting plates for a plurality of outer condenser tubes 31. The condenser tubes 31 are equal in number to the fractionating units 17, and are so spaced that they are located each directly above a corresponding fractionating tube 17 when the column as a whole is assembled.

Also clamped between the sections 1 and 3 is 10 a plate 33 which comprises the support for a plurality of connecting tubes 35 (Figures 1B and 2B). The connecting tubes 35 project a few inches into the fractionating columns or tubes 17, and are cut off slopingly on their lower ends within the 15 tubes 17. The upper ends of the tubes 35 are positioned directly beneath the condenser tubes 31 so as to deliver vapor thereto and receive condensed liquid therefrom.

Between the top flange 29 of the intermediate 20 section 3 and the bottom flange 37 of the top section 5 is clamped another ring 39 which is in all respects similar to the ring 25. A plate 41 on the upper end of the ring 39 supports inner condenser tubes 43, which project downwardly into the 25 outer condenser tubes 31 (Fig. 2A) throughout substantially the entire length of said outer tubes 31. The tubes 43 have closed ends which terminate in rods 45, which in turn project downwardly through the remainder of tubes 31, and a 30 part of connecting tubes 35. The ring 39 has gas outlet pipes 47 (Fig. 1B).

The top section 5 which is the shortest of the several sections, has a water inlet pipe 49 leading therethrough, and an overflow pipe 51 which 35 terminates close to the top of said section 3.

Between the top flange 53 of the top section 5 and the flange 55 of the dome-top 11 is clamped a plate 57, which plate 57 supports innermost condenser tubes 59. The innermost tubes 59 extend downwardly into the tubes 43 nearly to the bottom thereof. At the top of the dome 11 is a water outlet pipe 61.

When assembling the various parts, all parts 45 not stated to communicate are presumed to be sealed together in a leak-proof manner with gaskets or the like.

All of the tubes 31 are equal in length, as are the tubes 43 and 59, respectively. This is to 50 provide equal condensing surfaces in each of the individual condensers.

The operation of this embodiment of the invention is as follows:

Water for condensing purposes is admitted 55 through the pipe 49, and it immediately establishes a level in the upper section 5. The condensing water then flows, in equal streams, downwardly into tubes 43, filling said tubes, and overflows by rising in tubes 59 to the dome 11, whence, 60 after a suitable level has been built up it discharges through pipe 61. This system provides for an equal condensing capacity in each of the condenser systems, as the water flowing through each condenser is at the same temperature and is 65 flowing at the same rate, and the condensing areas in each condenser are equal. This, it will be remembered, was one of the conditions heretofore pointed out as desirable for the proper operation of the tower.

Vapors entering the column through pipe 9 are 70 in a relative state of equilibrium due to the large diameter of pipe 9. They therefore impinge upon and divide themselves into equal streams flowing into each of the fractionating tubes 17. It is 75

assumed that reflux liquid is already travelling downwardly in the tubes 17. The fractionation of the vapors now goes on in the described manner through the packed columns 17, each column operating in exactly the same manner because it is receiving the same amount of vapor and of reflux liquid and because it contains the same amount of packing material.

When the vapors reach the top of tubes 17 they have been scrubbed effectively. Here they divide into two paths. The larger portion of the vapors pass out through the top of tubes 17, into the ring 25 and thence through outlets 21 to the usual condensing apparatus. The remainder of the vapors pass through the lower ends of connecting tubes 35 and into the condensers, where they are condensed by contact with the water-cooled inner tubes 43. Such non-condensable gases and the like as are present pass from the top of the condenser tubes 31 and out through outlets 47. The condensed vapors constitute replenishments of the reflux liquid, and fall downwardly with gravity and are distributed into the fractionating tubes 17.

It will be seen that the ratio of vapors passing out of the tubes 17 entirely, to those passing into the condensing systems, are equal in all of the tubes, for this is controlled by the area of the opening of the connecting tubes 35, which are all equal.

Thus, a tower is provided which is made up of a plurality of unit columns, each of which carries an identical amount of vapor, fractionates it to an identical extent, and distributes identical proportions to the product outlet and to the individual condenser systems, wherein identical condensing conditions prevail, so that identical volumes of reflux liquid are delivered into each of the individual fractionating columns for treatment of further vapors.

The reflux liquid remaining at the bottom of the fractionating columns flows back through the pipe 9 to the still or other suitable device for effecting vaporization. Or, a trap may be provided for collecting these heavier residues.

In certain cases, it is desired to take off or cut distillate fractions intermediate to those issuing from the top of the tower, and/or to add vapors to be fractionated. This is provided for by the arrangement shown in Figs. 4, 5, and 6. Referring to Fig. 4, it will be seen that the fractionating section 1 is broken up into a plurality of sections 1a, 1b, and 1c, all of which are identical to the section 1 heretofore described. Between these sections are provided sections 63 (see also Figures 5 and 6) which are also vapor redistribution sections. Each section 63 has an upper flange 65 and a lower flange 67, the upper flange 65 extending across the section as a supporting plate for tubes 69 which fit against the tubes 17 of the fractionating section next above. The tubes 69 are constricted at their lower ends into smaller delivery tubes 71, which extend a short distance below the lower flange 67, so as to fit into the upper ends of the fractionating tubes 17 in the section next below. Holes 72 are provided near the ends of the tubes 69. Into the sections 63 project vapor tubes 73, 75, and 77. Tube 73 is the largest in diameter and has spaced holes 79 therein. Tube 75 is smaller, but extends nearly to the center of the section. Tube 77 does not project into the section at all, but merely constitutes a peripheral opening or outlet from the section. The arrangement of the tubes 73, 75, and 77 is such that substantially equal quan-

tities of vapor are drawn from or added to all parts of the section, so that no vapor surging results to cause faulty redistribution of the vapor into the fractionating tubes 17 of the next section above.

In operation, the sections 63 serve to gather together the vapors from all of the tubes 17, permit an even withdrawal of vapor therefrom and/or addition of vapor thereto, and redistribute the vapors into the tubes 17 of the next section above for further fractionation. The reflux liquid is not commingled, as it passes downwardly through the tubes 17 into the individual columns of the next section below, maintained in its individual streams. The quantity of vapors removed may be regulated by the rate at which they are condensed, as a faster condensing rate sets up a vacuum condition which results in drawing more vapors from the column.

The redistribution sections may be established at as many places as may be desired. Further, the intermediate fractionating sections can be made equal in length, or of different length, depending upon the character of the intermediate products desired.

While the pressure drop from top to bottom in the apparatus thus far disclosed is not prohibitively high, it is in some instances (such as the vacuum distillation of lubricating oils) too high for ready accommodation of the oils being distilled. This is occasioned by the frictional resistance offered to the vapors by the closely confined packing material in the tubes 17. The embodiment of the invention shown in Figures 8A through 13 is designed particularly to secure a minimum pressure drop, and is thus adapted particularly for vacuum distillations. This embodiment follows the same general principles as the embodiment heretofore described, but instead of drawing the vapors through confined packing material in a narrow tube, the tube is replaced by a rod which carries elements to effect a devous flow of the reflux liquid, and the vapors are not separated into several streams but are passed in a single stream in contact with the several reflux liquid streams (which are maintained separate) on the rods. Identical condensing systems of the same type as in the previous embodiment provide for equal volumes of reflux liquid on each of the rods.

Referring now more particularly to Figures 8A and 8B, numerals 101, 103 and 105 indicate bottom, intermediate, and top, shell sections, each provided with suitable joining flanges. Below the bottom section 101 is a connecting section 107 which connects the tower, preferably, directly to the still 109. A top dome section 111 is attached to the top section 105.

The lower flange 113 of the lower section 101 extends across said section as a plate, as shown in section in Fig. 11, and serves to support the lower ends of a plurality of parallel, closely spaced rods 115. Holes 117 between the rods 115 permit entrance of vapors into the fractionating section in a uniformly distributed manner, and also permit egress of reflux liquid reaching the lower ends of the rods.

The top flange 119 of the section 101 is joined directly to the bottom flange 121 of the section 103. Neither of these flanges extends across its section as a plate.

Near the bottom of intermediate section 103 is provided a portion 123 of increased diameter, which portion houses a condensing coil 125. An annular channel or trough 127 downwardly terminates the portion 123, and a drain 129 leads

from said channel. Near the top of the section 103 is provided an outlet pipe 131, by which the vacuum for the distillation is drawn.

The top flange 133 of the section 103 extends across said section as a plate, and supports the upper end of outer condenser tubes 135. The lower ends of the tubes 135 (see Fig. 9) are closed, and to them are welded the upper ends of the rods 115. Thus the rods 115 are, in effect, supported by the outer condenser tubes 135.

Upper section 105 is similar to its corresponding section in the first embodiment of the invention, and carries water inlet pipe 137 and water overflow pipe 139. The upper flange 141 of this section extends across the section, and serves to support inner condenser tubes 143 which are concentric with the outer condenser tubes 135, and extend downwardly therein for the majority of their length.

10 The top dome section 111 is provided at its top with a water outlet pipe 145.

Each of the rods 115 carries thereon a plurality of flow-breaking elements, which in the present embodiment comprise discs 147 (see also Figures 5 9 and 13). The discs 147 are arranged at different heights on the various rods and are of such diameter that they touch no rod except the one to which they are affixed. They constitute elements tending to give the descending reflux liquid a deviating path, and at the same time keep the streams on the several rods entirely separate. In this manner the area for liquid-to-vapor contact is increased. Fig. 13 is purposely exaggerated as to the number of discs and the closeness with which 15 they are spaced in order to show how they are placed without contacting adjacent discs or rods.

The operation of this embodiment of the invention is as follows:

Vapors enter the lower section 101 in the manner described. They rise through the fractionating section in a single stream, but contact with a large area of reflux liquid on the rods 115, with their attached discs. When they reach the top of the fractionating section 101, they have been effectively scrubbed and are free of heavier products. In the lower part of the section 103, a part of the vapors come into contact with the cooling coil 125 and are condensed, to fall into the annular channel 127 whence they are withdrawn 20 through the outlet 129 as the product. The remainder of the vapors continue upwardly to come in contact with the water-cooled tubes 135. As the flow of vapors is even across the column, the condensation on each of the tubes 135 is equal, 25 and the condensed vapors (now comprising the reflux liquid) run down the tubes 135 and on to the rods 115 to commence their downward travel through the fractionating section. The water flow in the condensing system is equal for each 30 tube and takes place in the same manner as that set forth in connection with the description of the first embodiment.

Residual fixed gases, if any, pass from the apparatus through the outlet 131.

While the embodiment just described is not in the strictest sense a "packed" type of fractionating power, it will be seen that in operation it is effectively the same as a packed column as the reflux liquid is given a devious path in flowing countercurrent to and in intimate contact with the vapor stream. As there is no packing material in a closely confined space, there is no vapor friction which would give rise to a great pressure drop. A tower six inches in diameter and about ten feet tall built in accordance with the above description

has been found to have a pressure drop of the order of one millimeter of mercury.

It will be understood that the rod and disc method of conducting the separately formed reflux liquid streams down through the fractionating tower is but one of the many methods that could be used with equal success. For example, the rods might be replaced by lengths of chains, or the rods might be retained but given a highly irregular surface to increase the area of reflux liquid in contact with the ascending vapor stream.

It will be readily seen that the fundamental characteristic of similarity between the several embodiments of the invention is found in the separate formation and separate maintenance of 15 a plurality of reflux liquid streams of equal size and surface area, and the separate streams being brought into intimate contact with a counterflow of vapors to be fractionated, and the streams being formed from a portion of the fractionated vapors reaching the top of the tower.

Throughout this specification, the separate fractionating units (small diameter columns or rods, as the case may be) have been described as of equal diameter or as carrying equal streams 25 of reflux liquid, and the condensers have likewise been described as of equal condensing capacity. This equality has been provided for the purpose of securing equal ratios of vapors to refluxing liquid at each of the units. Such 30 equal ratios of vapors to refluxing liquid may likewise be achieved by so proportioning the apparatus that if one column or rod, for example, is of a greater diameter and carries a greater volume of reflux liquid obtained from a 35 condenser of greater condensing capacity, then that column or rod shall receive a proportionately greater volume of vapors than smaller diameter columns or rods.

In view of the above, it will be seen that the 40 several objects of the invention are achieved and other advantageous results attained.

As many changes could be made in carrying out the above constructions without departing from the scope of invention, it is intended that 45 all matter contained in the above description or shown in the accompanying drawings shall be interpreted as illustrative and not in a limiting sense.

I claim:

1. The method of fractionating vapors which comprises introducing said vapors, originally in a unit stream, into intimate contact with a plurality of substantially separately maintained streams of refluxing liquid, the refluxing liquid flowing countercurrent to the vapors, whereby the vapors are scrubbed of their heavier components, bringing scrubbed vapors into contact with a plurality of separate condensing means, 55 thereby separately forming each of said plurality of separate streams of refluxing liquid, and maintaining at all times at each of said separate streams a substantially equal ratio of vapors to refluxing liquid.

2. The method of fractionating vapors which comprises introducing said vapors, originally in a unit stream, into intimate contact with a plurality of substantially separately maintained streams of refluxing liquid, the refluxing liquid 70 flowing counter to the vapors, whereby the vapors are scrubbed of their heavier components, bringing scrubbed vapors into contact with a plurality of separate condensing means, thereby separately forming each of said plurality of separate 75

streams of refluxing liquid, maintaining at all times at each of said separate streams a substantially equal ratio of vapors to refluxing liquid, and withdrawing a product portion after 5 said vapors are scrubbed but before the condensed scrubbed vapors are formed into said liquid refluxing streams.

3. The method of fractionating vapors which comprises introducing said vapors originally in 10 a unit stream, into intimate contact with a plurality of substantially separately maintained streams of refluxing liquid, the reflux liquid flowing countercurrent to the vapors, whereby the vapors are scrubbed of heavier components, re- 15 combining said scrubbed vapors into a unit stream and from said unit stream of scrubbed vapors, withdrawing a portion as product vapors, while bringing the remainder of said scrubbed vapors into contact with a plurality of 20 separate condensing means, thereby separately forming each of said plurality of separate streams of refluxing liquid, and maintaining at all times at each of said separate streams a substantially equal ratio of vapors to refluxing liquid.

25 4. The method of fractionating vapors which comprises introducing said vapors, originally in a unit stream, into intimate contact with a plurality of substantially separately maintained streams of refluxing liquid of substantially equal 30 size, the reflux liquid flowing countercurrent to the vapors, whereby the vapors are scrubbed of heavier components, recombining the scrubbed vapors into a unit stream, and from said unit stream of scrubbed vapors, withdrawing a portion 35 as product vapors, while bringing the remainder of said scrubbed vapors into contact with a plurality of separate, substantially equal, balanced condensing means, thereby separately forming each of said plurality of equal separate 40 streams of refluxing liquid.

5. The method as set forth in claim 4, in which each separate stream of reflux liquid is maintained as a unit packed fractionating column.

6. The method as set forth in claim 4, in which 45 the vapor stream is maintained as a single stream, in contact with said plurality of reflux streams throughout the fractionating step.

7. Fractionating apparatus comprising a tower made up of a plurality of relatively small-diameter 50 packed fractionating columns, means including a jacket confining said columns in parallel relationship in said tower with dead air spaces surrounding the said columns, said jacket and said air spaces maintaining said columns under 55 substantially equal temperature conditions, and a plurality of individual condensers arranged to deliver one into each of said columns.

8. Fractionating apparatus comprising a plurality of relatively small-diameter packed fractionating columns, a tower confining said columns in parallel relationship, and a separate condenser delivering into the top of each of said packed columns, each of said columns having substantially the same fractionating characteristics 65 and each of the condensers having substantially the same condensing capacity, means for distributing the vapors to be fractionated substantially equally into said plurality of columns, means for withdrawing from each of said columns a substantially equal proportion of the fractionated vapors therein, and means conducting the remaining fractionated vapors into the condensers associated with the respective columns.

75 9. Fractionating apparatus as set forth in

claim 8 in which all of said condensers are arranged in parallel relationship, and unitary condenser feeding means and discharging means for all of said condensers.

10. Fractionating apparatus as set forth in 5 claim 8 in which at least one redistributing section is provided intermediate the ends of said packed columns, said redistributing section including means for combining the vapors in all of said columns and redistributing the vapors 10 equally to each of said columns, but without combining the reflux liquid streams in the separate columns.

11. Fractionating apparatus as set forth in 15 claim 8 in which at least one redistributing section is provided intermediate the ends of said packed columns, said redistributing section including means for combining the vapors in all of said columns and redistributing the vapors 20 equally to each of said columns, but without combining the reflux liquid streams in the separate columns, and means for adding vapors to said redistributing sections without disturbing the equal distribution characteristics of said redistributing sections.

25 12. Fractionating apparatus comprising a plurality of separate fractionating units, a tower enclosing said units and maintaining said units in parallel relationship, said units comprising parallel condensers of substantially equal condensing capacity disposed near the top of said tower, means extending downwardly from each of said condensers adapted to conduct the liquid condensed thereon in separate streams to the bottom of said tower, means for admitting vapors 30 to be fractionated to said tower and conducting said vapors upwardly in said tower, and means for withdrawing a product portion from said tower at a point just below said condensers, allowing the remainder of said vapors to strike 35 said condensers to be condensed thereon, the said means extending downwardly from said condensers being constructed to compel the liquid flowing thereon to take a devious path exposing a relatively large surface area of liquid.

45 13. Fractionating apparatus comprising a plurality of separate fractionating units, a tower enclosing said units and maintaining said units in parallel relationship, said units comprising parallel condensers of substantially equal condensing capacity disposed near the top of said tower, means extending downwardly from each of said condensers adapted to conduct the liquid condensed thereon in separate streams to the bottom of said tower, means for admitting vapors 50 to be fractionated near the bottom of said tower and conducting said vapors upwardly in said tower, and means for withdrawing a portion of said vapors from said tower at a point just below said condensers, allowing the remainder of said 55 vapors to strike said condensers to be condensed thereon, the said means extending downwardly from said condensers comprising parallel rods with spaced discs attached thereto.

65 14. Fractionating apparatus comprising a plurality of separate fractionating units, a tower enclosing said units and maintaining said units in parallel relationship, said units comprising parallel condensers of substantially equal condensing capacity disposed near the top of said 70 tower, means extending downwardly from each of said condensers adapted to conduct the liquid condensed thereon in separate tortuous-path streams to the bottom of said tower, means for admitting vapors to be fractionated near the 75

bottom of said tower and conducting said vapors upwardly in said tower, and means for withdrawing a portion of said vapors from said tower at a point just below said condensers, allowing the remainder of said vapors to strike said condensers to be condensed thereon, the said means for withdrawing a portion of the vapors com-

prising a separate condenser in the form of a coil surrounding said units near the top thereof, said coil being adapted to condense a portion of the vapors, and a trough concentric with and beneath said coil for removing the condensed vapors from the tower. 5
